HOIST

Frank P. Lawler, Chicago, Ill., assignor of one-third to Charles H. Grant, San Francisco, Calif., one-third to Frank P. Lawler, Chicago, Ill., and one-third to Paul J. Tyler, Oroville, Calif., jointly

Application April 5, 1944, Serial No. 529,883

10 Claims. (Cl. 254—187)

1

This invention relates to a hoisting unit particularly adapted to be mounted in direct alignment with or in front of a driving shaft, for instance the front power takeoff shaft or the rear power takeoff shaft of a tractor or the like.

The object of the present invention is generally to improve and simplify the construction and operation of hoists which are especially designed for application to tractors for use in actuating bulldozers, trail builders, and other earth-moving or road-building equipment or the like; to provide a cable-winding hoist having a relatively high ratio of gear reduction interposed between the driving shaft and the driven cable drum so that it may be employed in connection with and directly connected to the driving shaft of any high speed tractor engine or any other high speed prime mover; to provide a hoist in which a clutch or power-engaging element is operative directly on the high speed driving shaft and which is so arranged that all of the reduction gearing and the hoisting elements will remain stationary or static whenever the clutch is disengaged, thereby enabling the hoist to be directly connected to a constantly running high-speed power supply shaft without necessity of any of the reduction gearing or hoisting elements rotating at any time except when the hoist is in use for pulling in or paying out the hoisting cable; to provide a cable winding hoist which is arranged so that all of the reduction gearing and hoisting elements employed remain stationary except when the hoist is in actual operation and which will, therefore, impose a minimum parasitic frictional drag on the power supply unit when the power shaft is constantly running and the hoist unit is inoperative; to provide a hoist in which the driving clutch is interposed between the power supply and the reduction gearing which operates the cable winding drum and in which the retarding or stopping brake operates directly on the relatively slow speed cable drum, said clutch and brake being operated by a single control lever arranged for proper sequence of engagement and disengagement to control the pulling in and paying out of the hoisting cable; and, further, to provide a hoisting unit in which the high speed driving shaft and the low speed driven drum are in substantial alignment and in which the reduction gearing and driving clutch are enclosed within a pair of connected cable winding and brake drums so as to form a most compact hoisting unit and to exclude dust, dirt, moisture, etc.

2

The hoist is shown by way of illustration in the accompanying drawings, in which:

Fig. 1 is a central, vertical, longitudinal section of the hoist;

5 Fig. 2 is a cross section taken on line 2—2 of Fig. 1, and

Fig. 3 is an end view showing the control lever and the mechanism actuated thereby.

Referring to the drawings in detail, and particularly Fig. 1, A indicates an exterior housing or support which may be built up of welded end sections such as indicated at 2 and 4 and an intermediate section 3. Formed in the end sections 2 and 4 are aligned openings 2a and 4a, and supported and secured in said openings is a housing B which serves several functions—first, that of enclosing and supporting a reduction drive gear train together with a cooperating clutch, and, secondly, that of a bearing support 15 for a cable drum C and a connected brake drum D.

The housing B has a central enlarged portion 5 and a pair of hub-like extensions 6 and 7 at opposite ends thereof. The hub 7 extends into 25 and is supported in the opening 4a while the hub 6 extends into the opening 2a where it is secured both against endwise movement and rotation by bolts 8 or similar means. A bearing 9 is disposed within the hub 7 and journaled 30 therein is a drive shaft 10 which may be coupled to a prime mover in any suitable manner. Formed within the enlarged portion 5 of the housing B is an annular extension 11 and mounted at the inner end of the hub 6 and in the extension 11 are bearings 12 and 14 in which is journaled a pinion 16 through which extends a driven shaft 15. Secured below shaft 15 in the enlarged portion 5 of the housing B is a journal pin 17 and rotatable on said pin are a pair of 35 connected gears 18 and 19, gear 18 meshing with the pinion 16 and gear 19 with an internal ring gear 20 which is secured within the brake drum D by means of bolts 21.

Where a hoist of this character is mounted 45 on a tractor, it is desirable that the gears remain at rest at all times except when the hoist is in operation, as gears running idle are subject to considerable wear and in addition thereto impose a considerable power drag on the prime mover. A clutch is accordingly provided, and this is interposed between the drive and the driven shafts. A cone-type clutch is here illustrated, the cone 23 of said clutch being carried by the driven shaft and the complementary cone 50 drum 24 by the drive shaft. Longitudinal move-

ment must, of course, be transmitted to the cone in order to connect or disconnect the clutch, and this is accomplished by forming a spline connection between the driven shaft and the pinion 16 driven thereby. In addition thereto, an internally threaded collar 25 is secured within the outer end of the hub 6. This threaded collar engages threads formed externally of the hub 26 which is provided with a lever 27. This lever when rocked in one direction or another partially rotates the hub 26 and thereby advances or retracts it with relation to the hub 6. The advancing movement being imparted to the driven shaft and the cone through means of a thrust bearing 28 and a collar 30 to engage the clutch and conversely permits disengagement of the clutch when retracted, the disengaging movement being aided by a spring 29, the main function of which is to maintain engagement between the thrust collar 30, the bearing 28, and the hub 26.

The cable drum C is in this instance formed integrally with the brake drum D. This is in turn provided with an end head 32 secured by bolts 33. The head is journaled as at 34 on the exterior surface of the hub 7, while the cable drum is journaled as at 35 on the hub 6, thus providing ample and widely spread bearing surfaces for the connected cable drum and brake drum to take care of any loads to which they may be subjected.

The brake drum is surrounded by a brake band 40. This band is anchored at one end to the housing A, as indicated, and is adjustably secured at the other end to a lever 41 pivoted as at 42 at one side of the housing. A spring 43 is attached to the opposite end of the lever and normally serves the function of applying the brake band so as to secure the brake drum and connected cable drum against rotation.

Hub 26, as previously stated, is provided with a lever 27 and also with a second lever 44. This latter lever is connected with lever 41 through a link 45 and lever 27 is similarly connected with lever 41 through a link 46. The links 45 and 46 are of a type which will transmit load in one direction only and act in opposition to each other; that is, if the lever 27 is swung in the direction of arrow a (see Fig. 3), link 46 will impart movement to lever 41 in the same direction while link 45 will merely become extended. Conversely, if lever 27 is swung in the opposite direction, link 46 will extend while link 45 will impart movement to lever 41. The extending movement of the links in opposition to each other is important as it permits the use of a single lever 48 to control all operations of the hoist. For instance, if the control lever 48 is moved in the direction of arrow a, such movement will be imparted to lever 27, and when this reaches the position indicated by line b, the brake band will be partially released and the cone clutch partially engaged, and when it reaches the position indicated by the line c, the band will be fully released and the clutch fully engaged, thereby permitting power to be transmitted through the reduction gear drive to drive the brake and cable drum. The full line position of lever 27, as shown in Fig. 3, is its neutral position. In this position the brake band is applied by the action of the spring 43 and the cone clutch is disengaged. Hence, if the lever is moved back to this position, the hoist becomes inoperative. When the brake band is disengaged and the clutch engaged, the cable drum is obviously operating or reeling in the cable. In practically all instances,

as the cable is being reeled in, it is lifting a load. Hence, means must be provided for lowering the load and for controlling the speed of lowering. This is readily accomplished in the present instance by merely swinging the control lever in the direction opposite to arrow a or to the position indicated by the line d. When this is done, link 45 acts on lever 41 to release or slacken its grip on the brake band by neutralizing the tension of the spring 43, the degree of release being, of course, controlled by the operator so that the load may be lowered at any speed desired, or it may be completely released if free reeling of the cable drum is desired.

From the foregoing it should be apparent that the gears in the reduction gear drive only rotate during the raising or lowering of a load and that they remain stationary at all other times. This is important, as previously stated, as it reduces the wear on the hoist operating parts and it substantially eliminates any drag on the prime mover. The entire structure is exceedingly compact, simple in construction and subject to control by a single lever. The gear reduction mechanism and the cone clutch are all housed within the enlarged portion 5 of the housing B, and, as this in turn is completely enclosed by the brake drum, it is obvious that water, moisture, dust, dirt, etc., are completely excluded and that leakage of lubricants contained within the hoist is maintained at a minimum.

While this and other features of my invention have been more or less specifically described and illustrated, I nevertheless wish it understood that changes may be resorted to within the scope of the appended claims, and that the materials and finish of the several parts employed may be such as the experience of the manufacturer or varying conditions or use may demand.

Having thus described and illustrated my invention, what I claim and desire to secure by Letters Patent is:

1. In a hoist of the character described, a housing, a connected brake drum, cable drum and head member enclosing and journaled on the housing, a drive shaft journaled in one end of the housing, a driven shaft journaled within the housing, a reduction gear drive journaled within the housing and forming a drive between the driven shaft and the connected drums, a clutch within the housing for connecting or disconnecting the drive and driven shafts, a brake band surrounding the brake drum, and a common means for substantially simultaneously releasing the brake band and engaging the clutch, or vice versa.

2. In a hoist of the character described, a housing, a connected brake drum, cable drum and head member enclosing and journaled on the housing, a drive shaft journaled in one end of the housing, a driven shaft journaled within the housing, a reduction gear drive journaled within the housing and forming a drive between the driven shaft and the connected drums, a clutch within the housing for connecting or disconnecting the drive and driven shafts, a brake band surrounding the brake drum, and a common means for substantially simultaneously releasing the brake band and engaging the clutch, or vice versa, said means also adapted to release the brake band when the clutch is disconnected.

3. In a hoist of the character described, a housing having a central enlarged portion and a hub member at each end thereof, a connected brake drum, cable drum and head member sur-

rounding and enclosing the housing, said connected members being journaled on the respective housing hubs, a drive shaft journaled interior of one of said hub members, a driven shaft journaled within the central enlarged portion of the housing, a reduction gear drive also journaled within the enlarged portion of the housing, said gears forming a drive between the driven shaft and the connected drums, and a manually operated clutch within the housing to connect or disconnect the drive and the driven shaft.

4. In a hoist of the character described, a housing having a central enlarged portion and a hub member at each end thereof, a connected brake drum, cable drum and head member surrounding and enclosing the housing, said connected members being journaled on the respective housing hubs, a drive shaft journaled interior of one of said hub members, a driven shaft journaled within the central enlarged portion of the housing, a gear pinion on the driven shaft, a journal pin mounted in the enlarged portion of the housing, an internal ring gear secured to the brake drum, a pair of connected gears mounted on the journal pin, one of said gears meshing with the pinion on the driven shaft and the other with the internal gear to form a reduction gear drive between the driven shaft and the connected drums, and a manually operated clutch within the housing to connect or disconnect the drive and the driven shafts.

5. In a hoist of the character described, a housing having a central enlarged portion and a hub member at each end thereof, a connected brake drum, cable drum and head member surrounding and enclosing the housing, said connected members being journaled on the respective housing hubs, a drive shaft journaled interior of one of said hub members, a driven shaft journaled within the hub members, a reduction gear drive journaled within the enlarged portion of the housing, said gears forming a drive between the driven shaft and the connected drums, a manually operated clutch within the housing to connect or disconnect the drive and the driven shaft, means closing the outer end of each hub member to prevent escape of lubricant within the housing, and means preventing escape of lubricant between the ends of the cable drum and head member and the respective hub members on which they are journaled.

6. In a hoist of the character described, a housing, a connected brake and cable drum enclosing and journaled exteriorly of the housing, a drive shaft journaled at one end of the housing, a driven shaft journaled within the housing, a reduction gear drive journaled within the housing and forming a drive between the driven shaft and the connected drums, clutch means for connecting the drive and the driven shaft, a brake cooperating with the brake drum, a control lever and means actuated by said lever whereby when the lever assumes a neutral position the brake is applied and the clutch released, said lever when moved from neutral in one direction releasing the brake only and when moved from neutral in the opposite direction, causing substantial simultaneous engagement of the clutch and release of the brake.

7. In a hoist of the character described, a central housing, a hub member at each end thereof, a drive shaft, a driven shaft within the hubs and housing, a cable drum, a brake drum secured thereto a head member secured to the

said drums, said cable drum, brake drum and head member completely surrounding and enclosing the central housing and the hubs and journaled on the respective hubs, clutch means for engaging and disengaging the drive and driven shafts, and a reduction gear transmission within the housing for transmitting power from the driven shaft to the cable drum.

8. In a hoist of the character described, a central housing, a hub member at each end thereof, a stationary support, means securing the housing and hub members to said support, a drive shaft, a driven shaft within the hubs and housing, a cable drum, a brake drum secured thereto a head member secured to the brake drum, said cable drum, brake drum and head member completely surrounding and enclosing the central housing and the hubs and journaled with relation to the stationary support and the hubs, clutch means for engaging and disengaging the drive and driven shafts, and a reduction gear transmission within the housing for transmitting power from the driven shaft to the cable drum and connected brake drum.

9. In a hoist of the character described, a housing having a central enlarged portion and a hub member at each end thereof, said housing and hub members being secured to a stationary support, a connected cable drum, brake drum and head member enclosing the central housing, said connected members being journaled on the respective hub members, a drive shaft journaled interior of said hub members, a driven shaft journaled within the central enlarged portion of the housing, a reduction gear drive also journaled within the enlarged portion of the housing, said gears forming a drive between the driven shaft and the connecting drums, and a manually operated clutch to connect or disconnect the drive and driven shaft.

10. In a hoist of the character described, a housing, a connected brake drum, cable drum and head member enclosing and supported to rotate about the housing, a drive shaft journaled at one end of the housing, a driven shaft journaled within the housing, a reduction gear drive journaled within the housing and forming a drive between the driven shaft and the connected drums, a clutch within the housing for connecting or disconnecting the drive and driven shafts, a brake band surrounding the brake drum, and a common means for substantially simultaneously releasing the brake band and engaging the clutch, or vice versa.
